(57) **CLAIM**

The ornamental design for a gel pen, as shown and described.

DESCRIPTION

1. Gel pen

1.1 : Front

1.2 : Back

1.3 : Left

1.4 : Right

1.5 : Top

1.6 : Bottom

1.7 : Perspective

1.8 : Perspective

1.1 is a front elevation view of a gel pen showing our new design; 1.2 is a back elevation view thereof; 1.3 is a left side elevation view thereof; 1.4 is a right side elevation view thereof; 1.5 is a top plan view thereof; 1.6 is a bottom plan view thereof; 1.7 is a perspective view thereof; and 1.8 is a perspective view thereof; besides, the gel pen incorporating the new design is mainly used for writing; the drawing designated to best show the essential features of the design is 1.7.
